EXTENSION TABLE

Thurlow E. McFall, Sparta, Mich., assignor to
 Michigan Artcraft Company, Sparta, Mich., a
 corporation of Michigan

Application April 20, 1938, Serial No. 203,088

8 Claims. (Cl. 311—67)

This invention relates to extension tables and is concerned with a novel structure whereby a table is produced which in its collapsed condition occupies but little space, but which can be extended to any desired distance within reasonable limits for use as a dining room table, and when collapsed occupying no more than substantially one-half of the space which it occupies when in its smallest extended position.

10 The invention consists of novel structure by means of which the table can be extended and when extended is stably supported. At the same time the table structure is strong and durable.

An understanding of the invention may be had 15 from the following description, taken in connection with the accompanying drawings, in which:

Fig. 1 is a side view of the table in its smallest or collapsed condition.

Fig. 2 is a similar elevation illustrating the 20 first step of movement in extending the table.

Fig. 3 is a like view illustrating the next succeeding step.

Fig. 4 is an elevation showing the table extended.

25 Fig. 5 is a fragmentary plan view illustrating the table at substantially the position in Fig. 2, or during the first step of its extension.

Fig. 6 is a transverse section taken substantially on the plane of line 6—6 of Fig. 5, looking 30 in the direction indicated by the arrows.

Fig. 7 is a fragmentary transverse vertical section showing a modified detail of structure slightly different from the equivalent structure shown in Fig. 6.

35 Fig. 8 is a fragmentary plan view of a modified detail of structure, and

Fig. 9 is a vertical section through the structure as in the position shown in Fig. 2 and of a modified form from that which is illustrated in said 40 Figs. 2 and 5.

Like reference characters refer to like parts in the different figures of the drawings.

In the construction of the table a top member 1 is permanently secured to a table frame member having spaced apart sides 2 with an end member 3 extending between them adjacent their front edges, the adjacent edges of the frame members 2 and 3 having connection to vertical front supporting legs 4. In conjunction with the 45 front part of the table thus described, is a rear part which has a bottom 5 connected to the lower edges of two side members 6 and to a rear end frame member 7, the adjacent edges of the frame members 6 and 7 being connected to rear 50 vertical legs 8 in the same manner that the parts

2 and 3 are connected to the front legs 4. The side frame members 6 are located so as to move within the side frame members 2 of the first described section of the table. Extension slides are disposed between the two sections of the table 5 consisting of fixed bars 9 and 10, one at each side of the table and secured respectively, the bars 9 to the bottom 5 and in contact with the end members 6, and with the bars 10 secured to the under side of the top member 1 of the first described section. The intermediate slides 11 are slidably connected with respect to each other so as to separate the two sections of the table as shown in Fig. 5. The detail of the slides is not described as such slides are common and well-known.

A narrow top member 12 in the collapsed position of the table, as in Fig. 1, lies over the rear end frame member 7 and over the upper ends 20 of the rear legs 8 and is free of connection thereto and also free of connection of the frame members 6. At its rear edge a third top member 13 is hingedly connected thereto by concealed hinges 25 as at 14. The width of the top member 13 is equal to the combined width of the two top members 1 and 12, so that in the collapsed condition of the table, shown in Fig. 1, the top member 13 extends over both top members 1 and 12 and completely covers them as shown.

A slide 15 is permanently secured at one end 30 to the upper side of the bottom 5. It is slidably connected with guides which consist of two side bars 16 and a cover 17 (Fig. 6). This guide structure is secured at its rear portion to the under side of the narrow top member 12. A locking 35 catch 18 similar to that which is used with sliding windows passes through one of the side guides 16 and at its inner end may enter a recess in the side of the bar 15 (Fig. 5) to normally hold the top member 12 in a fixed position, such as shown 40 in Figs. 1 and 2, with respect to the rear section of the table comprised of the bottom 5, sides 6 and ends 7; but by withdrawing the catch 18, the top member 12, with the attached guides 16, 17 may be moved to a forward position, as in Fig. 3 or 4. 45

With a table as thus constructed and in the position where it occupies the smallest space, as in Fig. 1, to extend the table the upper top member 13 is lifted at its free forward edge and thereupon the forward section of the table is moved 50 by extending the slides 11, as in Fig. 2, the top member 12 remaining at its rear position by reason of the lock provided by the locking catch 18. After the front section of the table has been moved forwardly a desired distance, the catch 55

at 18 is withdrawn, and then the upper table top member 13, with the narrow member 12 hinged thereto is moved forward as illustrated in Fig. 3, the guides 16, 17 moving forward on the bar 15. 5 The final step is to swing the upper top member 13 over to horizontal position as in Fig. 4 and close any gaps which may exist between the front top member 1 and the narrow intermediate member 12. It will be evident that if desired the table 10 may be further extended, the narrow top member 12 spaced from the rear edge of the front top section 1, and within such space ordinary table leaves may be inserted so as to make a still greater extension of the table. The rear top 15 member 13, in Fig. 4, will extend a distance beyond the rear supporting legs 8, but the center of gravity of the table as a whole will be in front of the rear legs 8 so that the table is stable and will not readily tip.

20 In order to support the central portion of the table when it is extended, and particularly when it is extended by the use of additional table leaves, a cross bar 19, Figs. 5 and 6, is connected at its ends to the lower sides of one of the extension slide members 11, at each side of the table, as best shown in Fig. 5. Foldable legs 20 are pivotally connected at their upper ends at 21 by suitable brackets to the under side of the bar 19 and may be dropped down to vertical position, as 30 indicated in dotted lines in Fig. 6, to give additional support to the central part of the table.

In Fig. 8 instead of the narrow top member 12 being connected to a movable guide member 16, 17, it is secured by suitable fastenings shown at 35 22, to the rear ends of intermediate slides 11 of the table slide construction. This structure is an equivalent generally of the guiding structure 15, 16 and 17 shown in Fig. 6.

In Fig. 7 such slidable guide structure 15, 16 40 and 17 of Fig. 6 is replaced by the slidable guides 15a and 16a, the former within the latter. The guide members 15a and 16a are of identical structure, being merely reversed in position, the inner members 15a being secured to the bottom member 5 and the outer guide members 16a at their end portions to the narrow top member 12.

In Fig. 9 instead of the narrow table top member 12 being connected to a movable slide such as shown at 16, 17 in Fig. 6, it is connected pivotally to one end of parallel links 23, the other ends having pivotal connection by means of a plate 24 to the upper side of the bottom member 5. In this case, the movement of the narrow top member 12 instead of being a straight forward 55 movement, as in moving from the position in Fig. 2 to that in Fig. 3, is an arcuate movement controlled by the parallel links 23 as they are swung about their lower pivots to the left.

The construction described permits the extension of a table which in its collapsed condition occupies relatively small space, in fact not over half of what the table has when it is at its minimum extended position as in Fig. 4; and of course 60 the table can be still further extended beyond what is shown in Fig. 4 by the use of additional table leaves. The stability of the table and the strength of construction which can be attained when made as described, with the ability to 65 occupy small space, make this table very practical and serviceable. It has particular utility in those cases where room in a house or apartment is at a premium. For the table needs to occupy its extended position only during the few short intervals of the day at meal times, and all of the 70

other times occupy a minimum of space as shown in Fig. 1.

The invention is defined in the appended claims and is to be considered comprehensive of all forms of structure coming within their scope. 5

I claim:

1. In a table, two extensible frame sections having supporting legs at their outer portions, a top member permanently secured over one of said sections, a second narrow top member movably mounted with respect to the second section and adapted to be moved to the outer portion thereof when the extensible sections are brought together, or inwardly against the edge of the permanent top member when said sections are extended, and a third top member hingedly connected to the narrow top member and movable therewith and adapted to be swung in one position to cover both of the other top members, or at the other position to lie in the same horizontal plane therewith and be supported by the second 20 plane of said extensible frame sections, as specified.

2. In a table, a front and a rear frame section, the front section having supporting legs at its forward end and the rear section at its rear end, 25 a top member permanently secured over the front section, a bottom permanently secured at the lower side of the rear section, extensible slides between said top and bottom, a second relatively narrow top member located over the rear supporting legs when said sections are in non-extended position, and a third top member hingedly connected to the rear edge of the second top member and having a width equal to the width of the first and second top members and adapted 30 to cover the same when said frame sections are in non-extended position, said narrow top member adapted to be moved rearwardly with the rear legs when the sections are extended and be returned to its original position adjacent said first named top section leaving said legs in the rearward-extended position.

3. In a table, a front extensible table section having side frame members and an end frame member, a top located thereover and permanently secured thereto, front legs located adjacent the front corners of said top and extending vertically downwardly, a rear table section having spaced apart side members, a rear end member and rear vertical posts, and a bottom permanently secured at the lower portions of said side and end members, said side frame members of the rear section being adapted to move within the side frame members of the front table section, extensible table slides disposed in two groups 55 at opposite sides of the table above said bottom and below said permanently secured top member and connected thereto, whereby the two table sections may be telescoped together or extended with respect to each other, a second narrow top 60 member normally located over the rear end frame member and the upper ends of the rear legs, means for movably mounting said narrow top member for movement in a forward or rearward direction on and with respect to the rear table 65 section, and a third top member hingedly connected to the rear edge of the second and narrow top member and having a width equal to the combined widths of the first and second top members. 70

4. A construction containing the elements in combination defined in claim 3, combined with means for releasably securing the second and narrow top member to the rear table section whereby upon extending said sections with re- 75

spect to each other said second and narrow top member and the hingedly connected third top member remain in a fixed position with respect to the rear table section, being thereafter released and moved forwardly, and then the third and upper top member hingedly turned to the rear.

5. In a table, two extensible sections with table slides therebetween movable toward or away from each other to collapse or extend the table, a top member permanently secured over one of said sections, a bottom permanently secured to the other of said sections in a plane below said top member, a second and narrow top member over the second of said sections movable with said bottom away from said first named top member, parallel links pivotally connected at their ends respectively to said bottom and to said second and narrow top member, whereby said second top member can be returned to its original position when the sections are extended, and a third top member hingedly connected to the outer edge of said second and narrow top member, the width of said third top member equalling the combined width of the other two top members.

6. In a table, a front and rear frame section, the front section having supporting legs at its forward end and the rear section at its rear end, a top member permanently secured over the front section, a bottom permanently secured at the lower side of the rear section, extensible slides between said top and bottom, a second relatively narrow top member located over the rear supporting legs when said sections are in non-extended position, a third top member hingedly connected to the rear edge of the second top member and having a width equal to the width

of the first and second top members and adapted to cover the same when said frame sections are in non-extended position, and means for maintaining said second top member in fixed relation relative to the rear extensible section of the table 5 on moving the front section of the table forwardly for extension, said means being operable after the sections have been extended with respect to each other for movement of the second top member forwardly toward the first and permanently 10 secured top member.

7. In a table, a front and rear frame section, the front section having supporting legs at its forward end and the rear section at its rear end, a top member permanently secured over the front 15 section, a bottom permanently secured at the lower side of the rear section, extensible slides between said top and bottom, a second relatively narrow top member located over the rear supporting legs when said sections are in non-ex- 20 tended position, a third top member hingedly connected to the rear edge of the second top member and having a width equal to the width of the first and second top members and adapted to cover the same when said frame sections are in 25 non-extended position, a bar permanently secured to said bottom, guides slidably associated with said bar and secured to said second top member, and means for releasably securing guides to 30 said bar.

8. The combination of elements defined in claim 6, said means including a bar permanently secured to said bottom, guides slidably associated with said bar and secured to said second top member, and means for releasably securing said 35 guides to said bar.

THURLOW E. McFALL.
